UNITED STATES PATENT OFFICE.

CHARLES R. ROWE, OF EAST ORANGE, NEW JERSEY, ASSIGNOR TO BRANDES LABORATORIES, INC., OF NEWARK, NEW JERSEY, A CORPORATION OF NEW JERSEY.

ELECTROMAGNETIC SOUND-REPRODUCING SYSTEM.

Application filed January 28, 1926. Serial No. 84,497.

My invention relates broadly to electromagnetic sound reproducers and more particularly to a circuit arrangement for sound reproducers by which high efficiency and good tone quality may be obtained in sound reproduction over the entire scale of musical notes.

One of the objects of my invention is to provide an electromagnetic sound reproducing system in which a plurality of electron tube circuits are arranged to integrate the effect of signaling energy upon an electromagnetic system for reproducing sound at relatively large volume.

Another object of my invention is to provide an electromagnetic sound reproducing system in which a plurality of electron tube circuits are associated with a like number of electromagnetic driving devices arranged to operate upon a common vibratory member integrating the effect of signaling energy existing in each of the electron tube circuits for actuation of the sound reproducing system.

Still another object of my invention is to provide an electromagnetic sound reproducing system in which independent electron tube circuits are arranged to control independent electromagnetic driving units which actuate a common vibratory member, one of the driving units being designed for efficient operation over frequencies within a portion of the musical scale and the other of said driving units being designed for efficient reproduction at frequencies over the other portion of the musical scale, whereby the entire range of musical notes may be efficiently reproduced.

A further object of my invention is to provide an electron tube amplification system for operation of an electromagnetic sound reproducing apparatus which will efficiently respond over the entire range of musical notes for the efficient reproduction of sound at large volume and good tone quality.

Other and further objects of my invention will be understood from the specification hereinafter following, by reference to the accompanying drawings, in which:

Figure 1 illustrates diagrammatically the circuits of a sound reproducing system in association with a radio receiving apparatus for the reproduction of broadcast signaling energy; Fig. 2 is an enlarged theoretical

diagram showing the arrangement of the electromagnetic sound reproducing system and the electron tube circuits which control the sound reproducing system; Fig. 3 is a fragmentary view of a circuit arrangement having means for improving the tone quality of the reproduced sound; Fig. 4 illustrates diagrammatically an arrangement of windings in a common electromagnetic system with the windings disposed in separate electron tube circuits and each designed to respond efficiently to frequencies over a portion of the musical scale; Fig. 5 illustrates another circuit arrangement for the electromagnetic devices in the output circuits of independent tube systems; and Fig. 6 shows a circuit arrangement of a plurality of electron tubes and independent electromagnetic driving devices each efficiently responsive to a particular range of notes for the reproduction of all of the received tones at pleasing quality.

Heretofore in the art it has been difficult to reproduce sound efficiently over the entire musical scale. Loud speakers have been constructed to reproduce a portion of the musical scale with pleasing tone quality, but in doing so the tone quality of another portion of the musical scale has been sacrificed. In the middle register, that is, the range of frequencies which the speaking voice normally occupies, electromagnetic sound reproducers in general will be altogether satisfactory; however, in the reproduction of a violin solo where a varied range of high and low notes must be reproduced with a piano accompaniment such loud speakers normally lose the natural reproduction of the tones. My electromagnetic sound reproducing system has been developed with a view of securing efficient reproduction of all of the notes in the musical scale. The operation of the circuits results in bringing out a wealth of perfectly natural tones. A mellow, full, complete harmony without a trace of nasal tone may be reproduced. The fuller harmonics, wider range, and clarity possible in the electromagnetic sound reproducer of my invention has a definite and satisfying reality.

I provide independent electron tube amplification systems where the incoming signaling energy is delivered to a common input circuit but controls independent output circuits in which are arranged the windings

of independent electromagnetic driving devices. These driving devices operate in phase integrating the effect of incoming signaling energy upon a common vibratory member which may be connected to a suitable sound reproducing diaphragm. The forces upon the vibratory member are increased by this circuit arrangement for one electromagnetic driver tends to attract the vibratory member, while the other driving device is exerting repulsive forces upon the vibratory member. I may also arrange the electromagnetic driving systems in circuit arrangements where one system is efficiently responsive to frequencies over a portion of the musical scale, while the other driving system is efficiently responsive over another portion of the musical scale, thereby securing a blending of the reproduced notes for efficient reproduction of sound over the entire musical scale.

Referring to the drawings, my invention is illustrated in Fig. 1 as applied to a broadcast receiving system having an antenna-ground radio frequency pick up circuit 1-2 with a radio frequency amplifier comprising electron tubes 3-4 connected therewith, a detector tube 5 connected to the output of the radio frequency amplifier, and an impedance coupled audio frequency amplifier system consisting of tubes 6-7 and the separate electron tube circuits which connect with electron tubes 8 and 9 connected with the output thereof. Electron tube 8 contains cathode 8^a, grid 8^b and plate 8^c, and correspondingly, electron tube 9 contains cathode 9^a, grid electrode 9^b, and plate electrodes 9^c. The input circuits of each of the tubes between grid electrode 8^b and cathode 8^a, and grid electrode 9^b and cathode 9^a, are connected through an impedance coupled audio frequency amplifier constituted by tubes 6-7. In the output circuit of electron tube 8 I provide windings 11 and 11^a connected in series and wound upon the electromagnetic system 17 having a magnetic reluctance gap 26 therein. In the output circuit of electron tube 9 I provide a pair of windings 12 and 12^a wound upon electromagnetic system 18 having magnetic reluctance gap 27. The electromagnetic systems are both arranged to actuate a common vibratory member 14 which may be connected through a rod 15 with a sound reproducing diaphragm 16. Sources of potential are provided for energizing the cathode circuit for each of the tubes as represented at 21. The plate supply for detector tube 5 is connected across terminals 20, while the plate supply for the amplifying tubes 3, 4, 6, 7 and the divided tube circuit 8-9 is supplied through terminals 19-29.

In Fig. 3 I have illustrated the electromagnetic driving systems disposed in the output circuits of each of the tubes 8-9

where the windings 11-11^a and 12-12^a are removed from direct connection in the plate circuits and connected in such manner that windings 11 and 11^a are related to an audio frequency choke coil 22 and condenser 23, 70 while windings 12-12^a are related to an audio frequency choke coil 25 and a condenser 24. A midtap connection 28 between the separate sets of windings is taken to the source of filament lighting potential 21. 75

In Fig. 4 I have illustrated the windings 11-11^a and 12-12^a disposed on the same set of pole pieces 17 where one set of windings 11-11^a is designed for efficient reproduction at high frequencies, that is to say the windings have a relatively low impedance, and windings 12-12^a on the other hand are designed for efficient reproduction of the lower frequencies and have a relatively high impedance. The conjoint effect 85 of these windings on the vibratory member 14 is to secure efficient reproduction over the entire range of musical notes.

In Fig. 5 I have shown the separate electromagnetic driving devices connected 90 through transformer systems 30 and 31 with the output circuits of tubes 8 and 9.

In Fig. 6 I have illustrated an electromagnetic sound reproducing system wherein tubes 8, 9 and 32, each excite the windings 95 11-11^a, 12-12^a, and 33-33^a, operating upon armatures 14, 34 and 35, respectively, the electromagnetic systems and armatures each being efficiently responsive, so that in aggregate the resulting effect is a substantially 100 perfect blending of all frequencies over a particular range of notes. The several armatures may be connected to different sound reproducing diaphragms of differing natural periods. 105

The operation of the electromagnetic sound reproducing system is such that with the two plate circuits of tubes 8 and 9 operating in phase, the electromagnetic windings 11-11^a will develop repulsive forces with respect to vibratory member 14, while windings 12 and 12^a develop attractive forces upon vibratory member 14 for imparting vibrations to the member 14 which are reproduced by a sound reproducing diaphragm 115 connected therewith. In the circuit arrangements illustrated in Figs. 3, 4 and 5 the separate output circuits of electron tubes 8 and 9 are arranged to cooperate for the reproduction of the signaling energy over the 120 entire musical scale with one portion of the circuit efficiently responding to frequencies of one band, while another portion of the circuit efficiently responds to frequencies of another band overlapping the first band for 125 uniformly reproducing notes of all frequencies. 110

It will be observed that the electromagnetic driving units are arranged in sets on diametrically opposite sides of the common 130

vibratory member 14. Each set of electromagnetic windings has the coils thereof wound in opposite directions. That is to say, winding 11 is wound in an opposite direction from winding 11^a, whereas winding 12 is wound in an opposite direction from winding 12^a. The effect of this is to normally polarize the electromagnetic driving units. That is, the pole pieces on which winding 11 is wound may be normally north, while the pole pieces on which winding 11^a is wound may be normally south. Correspondingly, the pole pieces on which winding 12 is located are normally south, while the pole pieces on which winding 12^a is located are normally north. The impression of incoming signaling energy on the input circuit 10 results in the operation of the plate circuits in phase and when winding 11 tends to reduce the strength of the normally north pole, winding 11^a tends to similarly reduce the strength of the normally south pole. Electron tube 9 operates simultaneously so that winding 12^a tends to strengthen the normally north pole, resulting in attraction of the vibratory member 14 in the direction of windings 12 and 12^a and with the releasing of magnetic force by windings 11 and 11^a. The next succeeding cycle will reverse the order of operation and in this manner reproduction at relatively large volume may be obtained.

While I have described my invention in certain preferred embodiments, I desire that it be understood that modifications may be made and that no limitations upon the invention are intended other than those imposed by the scope of the appended claims.

Having thus described my invention, what I claim and desire to secure by Letters Patent of the United States is as follows:

1. In an electromagnetic sound reproducing system, an electron tube amplification circuit, a pair of electron tubes having a common input circuit connected with said amplification circuit, an independent output circuit connected with each of said pair of electron tubes, an electromagnetic winding in each of said output circuits disposed in alignment with respect to each other, and a common vibratory member located between said electromagnetic windings upon which the magnetic effects of said windings are integrated.

2. An electromagnetic sound reproducing system comprising in combination an electron tube amplification circuit for increasing the amplitude of incoming signaling energy, a pair of electron tubes having a common input circuit connected with said amplification circuit, independent output circuits for each of said electron tubes, an electromagnetic winding in each of said output circuits, a common vibratory member actuated by said electromagnetic windings,

said pair of electron tubes being operated in phase whereby one of said electromagnetic windings exerts attractive forces on said vibratory member, while the other of said electromagnetic windings exerts repulsive forces thereon.

3. An electromagnetic sound reproducing system comprising in combination an electron tube amplification circuit, a pair of electron tubes having a common input circuit connected with said amplification circuit, independent output circuits for said electron tubes, a pair of diametrically opposed electromagnetic windings, connections between one of said windings and one of said output circuits and connections between the other of said windings and the other of said output circuits, and a common vibratory member positioned between said electromagnetic windings and actuated by signaling energy impressed upon said common input circuit.

4. An electromagnetic sound reproducing system comprising in combination an electron tube amplification circuit, a pair of electron tubes having a common input circuit connected with said amplification circuit, independent output circuits for said electron tubes, sets of oppositely wound electromagnetic windings connected in each of said output circuits for producing poles of opposite polarity, said sets of electromagnetic windings being arranged diametrically opposite each other with poles of opposite polarity adjacent each other, and a common vibratory member situated between said sets of electromagnetic windings and actuated by the conjoint effect thereof upon the impression of signaling energy upon said common input circuit.

5. An electromagnetic sound reproducing system, comprising in combination a pair of space discharge devices each including grid, filament and plate electrodes, an input circuit common to each of said grid and filament electrodes, means for impressing signaling energy upon said input circuit, independent output circuits connected to each of said plate electrodes, an independent electromagnetic winding included in each of said output circuits, a common vibratory member arranged to be actuated by said electromagnetic windings, and circuits for passing currents in phase through each of said independent electromagnetic windings and through the space path between said plate and filament electrodes in phase, integrating the effects of said signaling energy upon said common vibratory member.

6. In an electromagnetic sound reproducing system an electron tube amplification circuit, a plurality of electron tubes, a common input circuit for said tubes connected with said amplification circuit, independent output circuits for each of said electron tubes,

an electromagnetic winding disposed in each of said output circuits, said electromagnetic windings each being responsive to a different range of audio frequency notes and a 5 single armature member upon which said electromagnetic windings are each effective.

7. In an electromagnetic sound reproducing system an electron tube amplification circuit, a plurality of electron tubes each 10 having grid, filament and plate electrodes, a single circuit including all of said grid elec-

trodes, separate circuits, each including one of said plate electrodes, an electromagnetic winding included in series connection with each of said plate electrodes, each of said 15 electromagnetic windings being efficiently responsive to a different range of frequencies whereby notes over the entire musical scale may be efficiently reproduced.

In testimony whereof I affix my signature. 20

CHARLES R. ROWE.
